Inventor.

George S. Lewis,

By his attorney,

John C. Gifford,

Attest,

UNITED STATES PATENT OFFICE.

GEORGE S. LEWIS, OF OAK PARK, ILLINOIS.

WHEEL RIM AND METHOD OF MANUFACTURING THE SAME.

Application filed November 24, 1922. Serial No. 603,060.

To all whom it may concern:

Be it known that I, GEORGE S. LEWIS, a citizen of the United States, residing at Oak Park, in the county of Cook and State of Illinois, have invented a new and useful Improvement in Wheel Rims and Methods of Manufacturing the Same, of which the following is a specification.

My invention relates generally to metal wheel rims, but more especially to rims of cycle wheels which it is desired be of relatively light weight and still possess a high degree of strength.

One of the phases of my invention relates to the manner of producing metal wheel rims and the other phase thereof to the construction of the rim.

The object of my invention is to provide for the production of metal wheel rims which, while being relatively light in weight, shall possess a high degree of strength and which may be economically manufactured.

Referring to the accompanying drawings:—

Figure 1 is a face view of a completed rim constructed in accordance with my invention. Figure 2 is a view in cross section of the tubing from which the rim is formed in accordance with certain features of my invention. Figures 3, 4, 5 and 6 are cross sectional views of four different forms of rims, constituting certain of the many forms in which my invention may be embodied. Figure 7 is a cross-sectional view of another embodiment of my invention. Figure 8 is a similar view of still another form in which the invention may be embodied and involving a different method of production than in the case of the forms of the preceding figures; and Figure 9, an enlarged cross-sectional view of a rim showing the use of eyelets at the spoke-nipple openings therein.

Referring first to the structure shown in Figs. 1, 2 and 3, the rim is formed from a metal tube shown in Fig. 2, this tube being, by way of example, a piece of seamless steel tubing, or tubing formed from a strip of metal bent to form a tube with its adjacent edges welded, or otherwise united, to make a joint extending lengthwise of the tube. The tube of Fig. 2, in the forming of the rim, is pressed, by force applied crosswise thereof, into deformed condition, as for example,

into the cross-sectional shape shown in Fig. 3 to cause the deformed tube to present the transversely curved seating surface for the tire (not shown) which would encircle the rim, this seating surface being represented at 4 and extending, as will be understood, about the outer periphery of the rim in its finished state. The deforming of the tube, as stated, causes the rim to present the lateral hollow portions 5 at its opposite edges and between these portions a strip-portion 6 which flatwise opposes, and preferably contacts with, the inner surface of the part of the rim affording the seating surface 4, at the medial line of the rim, as represented in Fig. 3, it being preferred that these two flatwise opposed portions of the rim be welded together, as for example, by spot welding them at intervals about the circumference of the rim. The tube of Fig. 2 may be operated on to deform it as stated, in any desirable way, but preferably by passing the tube through forming-rollers, the peripheries of which are of such contour as to cause the tube to be deformed into the cross sectional shape shown in Fig. 3. The deformed tube is caused to assume curved form in a lengthwise direction to cause the rim, when finished, to be truly circular in form and of the desired diameter.

The curving of the deformed tube, as stated, may be effected in any desired manner, as for example, by causing the deformed end of the tube, as it issues from the deforming rollers, to engage a roller or other element so positioned as to deflect the deformed tube, as it moves against the roller, into the desired curved shape. The deformed tube, to form the continuous rim, is then welded at its abutting ends or otherwise united in any other desirable way.

In accordance with the common practice of providing openings in the rim between its marginal edges for receiving the nipples of the spokes of the wheel, the portion of the rim between the tubular portions 5 would contain such openings (not shown) which would preferably be arranged in staggered relation, in accordance with common practice.

The rim of Fig. 4 may be produced in the same manner as explained of the rim shown in Fig. 3, but in this case the deforming rollers would be so shaped as to cause the tube

to be deformed into the cross sectional shape shown in this figure instead of the shape shown in Fig. 3.

The construction of the rim shown in Fig. 5 may be formed as explained of the construction shown in Fig. 3, except that the tube deforming rollers are so formed as to roll the tube to the form shown in Fig. 5, in which form the metal located at the inner 10 periphery of the rim is deflected into contact with the metal forming the seating surface 4 at spaced apart points, at opposite sides of the medial line of the rim, as represented at 8, at which points these opposing metal portions are united together, as by 15 spot welding them at intervals.

The construction shown in Fig. 6 represents an embodiment of the invention where the body of the rim is made of relatively 20 soft metal, as for example, aluminum. This combination involves the provision of a strip, separate from the tube which is deformed to form the body of the rim, this strip serving to cause the rim to present additional metal at the central portion thereof. The construction of Fig. 6 may be made in the same way as that shown in Fig. 3 except that the tube-deforming rollers would be so shaped as to cause a space to be provided 25 between the part of the rim corresponding with the part 6 of Fig. 3, and the opposing portion of the tire-seating portion 4 thereof, of a height equal substantially to the thickness of the reinforcing strip to be 30 assembled therewith, and represented at 7. The strip 7 may be assembled with the body of the rim in any desired way and in accordance with any desired method of operation, as for example, by first deforming 35 the tube from which the rim is to be made, into substantially oval-shape in cross-section, then introducing the strip 7 into the partially deformed tube, and thereafter rolling the partially deformed tube and contained 40 strip into the cross-sectional shape shown in Fig. 6, it being preferred that this strip be of such length that its ends will overlap when the ends of the body of the rim are in 45 abutting relation. If desired, and by preference, the central portion of the rim, where it 50 presents the three thicknesses of metal, as shown, and at which the openings for the spoke nipples would be located, is spot welded at intervals around the circumference 55 of the rim, or these thicknesses of metal otherwise secured together.

It will be noted as to the constructions shown in Figs. 3, 5 and 6, that by reason of the relatively thick body of metal formed 60 between the lateral tubular portions of the rim, as compared with the relatively wide spacing of the walls of these tubular portions 5, the rim is caused to present great strength and sufficient to compensate for the 65 forming of openings therein for the spoke

nipples and cause the rim to present a high degree of strength, this being augmented, to a high degree, by the use of the separate reinforcing strip 7 in the construction shown in Fig. 6.

The construction shown in Fig. 7 also represents an embodiment of the invention where the body of the rim is formed of relatively soft metal, as for example, aluminum. It differs materially from the construction 75 shown in Fig. 3 and the method of manufacturing the latter, only in the particular that the hollow portions of the rim at its lateral edge portions contain tubing represented at 9, as for example, of steel which are provided to stiffen the rim. When the rim of this figure is formed by deforming a tube into the desired cross-sectional shape, the tube is deformed about the tubing 9 to cause the latter to be positioned in the rim 80 as shown, the adjacent ends of the tubing 9 being secured together in any desirable way, as by connecting them together by the use of dowels (not shown).

The construction shown in Fig. 8 constitutes another embodiment of the feature of my invention relating to the massing of metal adjacent the medial line of the rim, and is illustrative of a construction embodying this feature which may be formed of a 90 strip of metal instead of a tube. The producing of the rim of Fig. 8 involves the bending of a strip of metal into the cross sectional shape shown therein by any suitable means, as for example, by forming-rollers, as will be understood by those skilled in the art, the edges of the strip, these edges being represented at 10 and 11, overlapping 100 each other along the medial line of the rim and flatwise opposing the seat-forming portion 4 of the rim. These three layers of metal are provided along the medial line of the rim and are united in any desirable way, as by spot welding them at intervals. The strip formed into the cross sectional shape 105 shown in Fig. 8, is curved lengthwise thereof and its ends united to form the continuous rim, as explained in connection with the construction shown in Fig. 3.

The particular cross-sectional shapes 110 shown of the hollow portions at the lateral edges of the rims of Figs. 3 and 5 to 8 inclusive are by way of example only, it being understood that these portions may be otherwise shaped if desired. Furthermore, the 115 feature of the reinforced hollow portions (Fig. 7) may be incorporated in a rim formed from a flat sheet of metal as distinguished from forming it from a tube as described.

If desired, the openings in the rims for receiving the spoke-nipples may contain eyelets, this being especially desirable when the body of the rim is made of soft metal 120 preventing welding thereof, these eyelets 125

- preferably serving to reinforce the metal at the openings and secure together the flatwise opposed portions of the rim. The manner of providing the eyelets is represented in Fig. 9 wherein the eyelet is shown at 12 and where such are used with metal which may be welded, the welding of the flatwise opposed portions of the metal, as stated, may be dispensed with.
- 10 While I have illustrated and described certain forms of rim constituting embodiments of my invention, I do not wish to be understood as intending to limit it thereto, nor do I wish to be understood as intending 15 to limit the invention to the production of the rims by the methods as above explained, it being my intention to claim my invention as fully and completely as the prior state of the art will permit.
- 20 What I claim as new, and desire to secure by Letters Patent, is:
1. The method of forming metal wheel rims which consists in bending a tube of the metal from which the rim is to be formed, 25 to cause the central portions of the metal forming the tube to become flattened into contact with each other and the remaining portions of the tube to be in spaced relation, curving the deformed tube lengthwise thereof, and connecting together the ends of the deformed tube to form a continuous member.
  2. The method of forming metal wheel rims which consists in bending a tube of metal from which the rim is to be formed, 35 to cause the central portions of the metal forming the tube to become flattened into contact with each other and the remaining
- portions of the tube to be in spaced relation, curving it lengthwise thereof, inserting a 40 reinforcing strip into the tube, and connecting the ends of the deformed tube to form a continuous member.
3. The method of forming metal wheel rims which consists in positioning tubular 45 members in a tube from which the rim is to be formed, bending the tube to present hollow portions at its lateral edges and enclosing the tubular members therein, curving lengthwise the parts constructed as 50 stated and connecting together the ends of the deformed tube.
4. A metal wheel rim comprising a hollow member the wall of which is continuous in cross-section, the opposed wall portions 55 of said member intermediate the lateral edges of the latter being closely adjacent to each other and the portions thereof at the lateral edges of the member being relatively 60 widely spaced.
5. A metal wheel rim comprising a hollow member the wall of which is continuous in cross-section, the opposed wall portions of said member intermediate the lateral edges of the latter being closely adjacent to each other and the portions thereof at the lateral edges of the member being relatively 65 widely spaced, said first-referred-to wall portions being welded together at intervals.
6. A metal wheel rim comprising a hollow member the wall of which is continuous in cross-section and presents hollow portions 70 at its lateral edges, and reinforcing members in said hollow portions.

GEORGE S. LEWIS.
